(57) **CLAIM**

The ornamental design for a light and ultraviolet troffer, as shown and described.

DESCRIPTION

FIG. 1 is a bottom perspective view of a light and ultraviolet troffer showing my new design;

FIG. 2 is a top view of the ornamental design shown in FIG. 1;

FIG. 3 is a bottom view of the ornamental design in FIG. 1; FIG. 4 is a front view of the ornamental design shown in FIG. 1;

FIG. 5 is a rear view of the ornamental design shown in FIG. 1;

FIG. 6 is a side view of right side of the ornamental design shown in FIG. 1; and,

FIG. 7 is a side view of the left side of the ornamental design shown in FIG. 1.

The dashed lines illustrate the environment and do not form a part of the ornamental design disclosed and claimed herein.

1 Claim, 5 Drawing Sheets
